UNITED STATES PATENT OFFICE.

CHARLES A. MORIN, OF BOSTON, MASSACHUSETTS.

SHOE.

Original application filed September 11, 1924, Serial No. 737,060. Divided and this application filed February 2, 1925. Serial No. 6,432.

This invention relates to welt shoes, and is a division of my prior application, Serial No. 737,060, filed September 11, 1924, which matured into Letters Patent No. 1,528,260, granted March 3, 1925, to which reference is made as illustrating the method of producing the shoe involved in the present application.

My shoe is characterized by the fact that I use an insole having an inner channel extending a substantial distance below its outer face and having a portion of its edge face the full thickness of the insole formed to be inset from the outer edge of the bottom face of the last, whereby when the upper and welt are stitched to said inset edge face of the insole, the inseam stitches will be set in from the outer edge of the bottom face of the last and will lie in a plane intermediate of the upper and lower faces of the insole. This permits the under edge of the upper and lining and the inner edge of the welt to lie substantially flush with the outer face of the insole, i. e., in practically the plane of the insole edge, thereby affording a smooth, flat, level bearing for the foot inside of the shoe and for the outer sole.

The insetting of selected portions of the insole edge relative to the outer edge of the bottom face of this last may be variously accomplished, and in practice, I preferably accomplish this by forming the insole with a full feather and then deliberately removing the feather in the region of the shank and ball of the insole, so as to bring the edge contour of the insole at these points definitely within the bottom edge line of the last. This avoids all danger of forming an objectionable ridge at these points when the upper and welt are attached, due to the tendency of the usual feather at these points to curl up. The portions of the feather thus removed, or in other words, the portions of the insole edge thus set in from the outer edge of the bottom face of the last, may therefore be said to represent the natural over tread of the foot at these portions of the insole, and by having, or causing, the upper and welt to equal in thickness the inset edge face of the insole, I obtain at these points the smooth, level, flat bearing or tread foundation which characterizes my shoe.

Various expedients have been proposed for obtaining this characteristic flat tread foundation. It has been suggested that the feather could be wholly eliminated and instead the marginal edge of the insole molded back to provide an attaching lip for the upper and welt. This expedient, however, is open to the very objection which my invention aims to overcome; namely, the formation of a pronounced ridge on the top of the insole.

It has also been proposed to provide a featherless insole in which the edge face of the insole was exposed to the inseam stitching needles by leveling away the sides of the last, but such a shoe proved so expensive of manufacture and so difficult of production in commercial quantities and in all the varying widths, styles, and grades demanded by the trade, as not to be commercially practicable.

I can produce my shoe in commercial quantities and in all desired widths, styles and grades, on standard shoe making machinery, and at a cost no greater than the ordinary welt shoe, and I can incorporate into it a smooth, level, tread foundation which will remain smooth and flat throughout the life of the shoe.

In the accompanying specification and drawings, I describe and show a characteristic form of my shoe which has been found highly satisfactory in use and well adapted to the requirement of commercial production. Throughout the specification and drawings, like reference numerals are correspondingly employed, and in the drawings:

Fig. 1 is a bottom plan view of an insole contoured in accordance with my invention, the dotted line showing designated by the reference character X indicating the over tread of the foot on the insole at certain portions thereof.

Figs. 2 and 3 are transverse sections on the lines 2-2 and 3-3, respectively, of Fig. 1, and

Fig. 4 is a transverse section through the completed shoe.

I have indicated at 1 an insole having an inner channel 2 extending a substantial distance below its outer face and having a por-

tion of its edge face the full thickness of the insole formed to be inset from the outer edge of the bottom face of the last. This inset edge face portion of the insole lies in the 5 region of the shank and ball of the insole, and is indicated in dotted lines in Fig. 1 by the reference character X, which portion thus may be said to represent the overtread of the foot on the insole at these points.

10 Preferably, such insetting is accomplished by first providing the insole with a full feather 3 and subsequently removing those portions of the feather lying in the region of the shank and ball portion of the insole, 15 as designated at X in the dotted line showing of Fig. 1.

The insole thus has an inner channel 2 and a portion of its edge face the full thickness of the insole formed to be inset from the 20 outer edge of the bottom face of the last, or in other words, from the normal line of overtread of the foot on the insole at said portions.

After the insole has been thus channeled 25 and contoured, it is temporarily tacked to the last in the same manner as though it were of full feather contour, portions of the last bottom, however being exposed where the feather has been removed at X, Fig. 1.

30 The upper 4 and lining, if the shoe is lined, are next drawn over the insole, with their under edges in contact with the portions of the bottom face of the last exposed where the feather has been removed, and the 35 welt strip 5 is stitched to the upper and inset edge face of the insole by the inseam stitches 6, which stitches are thus set in from the outer edge of the bottom face of the last, that is, are set in from the normal overtread 40 of the foot on the insole at these points, and lie in a plane intermediate of the upper and lower faces of the insole.

The upper and welt are equal in thickness, or are subsequently trimmed off to equal in 45 thickness, the inset edge face of the insole, which face in the absence of the usual feather at these points, serves as a guide to facilitate the application of the welt strip to the insole, and hence afford a level, smooth and 50 flat foundation for the overtread of the foot at these portions of the insole.

By disposing the under edge of the upper and the inner edge of the upper in practically the plane of the insole, no filler is necessary in my shoe, although I preferably employ an extremely thin sheet of waterproof material as a moisture repellent.

60 In my shoe, therefore, certain portions of the insole edge at what may be said to be the points of natural overtread of the foot on the insole are deliberately inset so as to permit the welt and upper at these portions to be attached to said inset edge in the plane thereof, and thereby to afford a smooth flat 65 bearing for the foot, and for the outersole,

free of any objectionable ridges or lumps at the inseam.

By carrying the contour of the insole well about the toe, according to the style of shoe being made, shoes with toes of varying 70 widths may be lasted.

Various other modifications in the construction and assembly of my shoe may obviously be made within the spirit and scope of my invention, as defined by the appended 75 claims.

What I therefore claim and desire to secure by Letters Patent is:

1. A welt shoe, comprising an insole having an inner channel extending a substantial distance below its outer face and having a projecting feather, portions of which in the region of the ball and shank of the insole have been removed to bring the edge face of the insole at these points definitely 80 within the normal overtread of the foot on the insole at said points, and an upper and a welt stitched continuously to the insole along both its feathered and unfeathered portions, the inseam stitching along said unfeathered 85 portions being carried directly through the inset edge face of the insole and lying in a plane intermediate of the upper and lower faces of the insole whereby the normal foot contour overhangs said inseam at said unfeathered portions and is cradled on the lower margins of the upper.

2. In a welt shoe structure, a substantially flat insole adapted to contact throughout substantially its entire extent with the outer sole, said insole having an inner channel extending a substantial distance below its outer face and having portions of its edge face the full thickness of the insole formed to be marginally inset relative to the normal overtread of the foot on the insole at these 100 portions, and an upper and a welt stitched to said inset edge face of the insole by a line of stitching which lies in a plane intermediate of the upper and lower faces of the 105 insole, whereby the normal foot contour at said inset edge face overhangs the inseam stitches and is cradled on the lower margins of the upper.

3. In a welt shoe structure, a substantially flat insole adapted to contact throughout substantially its entire extent with the outer sole, said insole having an inner channel extending a substantial distance below its outer face and having portions of its edge 110 face extending from substantially its tip line to its shank the full thickness of the insole formed to be marginally inset relative to the normal overtread of the foot on the insole at these portions, and an upper and a welt stitched to said inset edge face of the insole by a line of stitching which lies in a plane intermediate of the upper and lower faces of the insole, whereby the normal 115 foot contour at said inset edge face over-

hangs the inseam stitches and is cradled on the lower margins of the upper, the under edge of the upper and the inner edge of the welt lying substantially flush with the outer face of the insole.

4. An insole having an inner channel extending a substantial distance below its outer face, and having a projecting feather, portions of which in the region of the ball and

shank of the insole have been removed to 10 bring the edge face of the insole the full thickness of the insole at these points definitely within the normal overtread of the foot on the insole at said points.

In testimony whereof I affix my signature.

CHARLES A. MORIN.
